UNITED STATES PATENT OFFICE.

JOHN C. McVEY, OF KANSAS CITY, MISSOURI.

DIRECTION SIGNAL.

Application filed August 17, 1925. Serial No. 50,666.

This invention relates to direction signals particularly applicable for use for indicating the direction in which a motor vehicle is to be turned, whether to the right, to the left, or whether the driver contemplates stopping. It is usually the custom to signal directions by using the left arm. If the driver is about to turn to the right the left arm is extended at an upward angle of about 45 degrees, if to the left at a downward angle of about 45 degrees, and if the driver is about to slow down the speed of the car or come to a stop, the arm is usually extended in a horizontal plane.

My invention contemplates a construction of signals in which a signal element will simulate the arm of the driver. The signal element may be provided with a source of illumination so that it will be visible in darkness as well as in the light.

The novelty of the invention will be understood by reference to the following description in connection with the accompanying drawings, in which—

Fig. 1 is a perspective view of the front portion of a motor vehicle to which my invention is applied, the signal element being shown in "stop" position.

Fig. 2 is a perspective view of the signaling apparatus showing the signal element in the position to indicate that the driver is about to turn to the right.

Fig. 3 is a longitudinal sectional view through the apparatus, the signaling element being in non-indicating position.

Fig. 4 is a sectional view through the casing for holding the signaling element, the signaling element being shown in elevation, the position indicating that the driver is about to turn to the left, and

Fig. 5 is a perspective view of the selector element.

There is a rectangular indicator-enclosing casing 1 having a vertical edge slot or opening 2 through which the signaling element 3 normally within the casing may be projected. The signaling element is shown as comprising a rectangular hollow frame having a central opening 4 in which is a light source such as an electric lamp indicated at 5. The lamp may be supplied with current from an electrical source such as a battery 6 through the conduits 7 and 8, there being a switch 9 to make and break the circuit in a well-understood manner. The rectangular signaling element 3 is secured to the casing

1 by a pivot 10 passing through the side walls of the casing and through the signaling element near one corner thereof. Therefore, the signaling element is adapted to be tilted or swung about the axis of the pivot 10. The casing 1 communicates with a vertical elongated guide conduit 11 having a right angular extension 12 in one wall 13 of which is a horizontal elongated slot 14. In the lower edge of the slot 14 are notches 15, 16, 17 and 18 which receive the stem 19 of a selector element 20 provided with a head or knob 22 by means of which the driver may operate the selector stem along the slot. The selector stem has an arm 23 which is connected to a flexible member shown as a wire coil 24 in turn fastened to the vertically disposed flat rod or bar 25. The upper end of the flat bar or rod is connected to the signaling element 3 by two links 26 and 27, the links straddling the rod 25 and being fastened thereto by the pivot 28. The opposite ends of the links are pivotally connected to the bracket arm 29 by the pivot 30. Therefore, if the operator moves the selector element in the slot from right to left the signaling element will be projected through the opening 2 in the casing to properly signal the direction in which the car is to be turned or to signal a contemplated stop. For example, if the stem 19 is in the neutral notch 18, the signaling element will be retracted within the casing. If the stem is in the notch 17 the element 3 will be caused to assume the position shown in Fig. 1, indicating that the driver is about to turn to the right. If the stem is in the notch 16 the signaling element will be in a horizontal plane indicating that the driver is about to slow down or stop the car. If the stem 19 is in the notch 15 the signaling element will be caused to assume the position shown in Fig. 4, in which event it will be apparent that the driver contemplates turning to the left.

The cable 31 carrying the conductors 7 and 8 is of sufficient length to provide a certain amount of slack indicated at 32 so that it may be paid out when the signaling element is projected or tilted through the slot or opening 2. The cable is preferably supported in the top by a cross pin 33.

A suitable fastening device may be employed to secure the signaling apparatus to the motor vehicle. The screw 34 will secure the casing and conduit 11 to the outside of

the motor vehicle, the lateral projection 12 extending inside the vehicle so that the selector will be within easy reach of the driver. The bottom of the conduit 11 and its extension 5 may be supported with respect to the bottom of the motor vehicle 35 by a plate 36 (see Fig. 1). In fact any suitable means may be employed for attaching the apparatus to the motor vehicle for either open or 10 closed cars. These obviously may be varied according to the whim of the manufacturer.

From the foregoing it will be apparent that the signal may be conveniently operated from the inside of a closed car so that the 15 signaling element will be visible from the outside of the closed car, and that the various positions normally assumed by the arm of a driver in indicating contemplated movements of the vehicle may be reproduced by 20 the element so that danger of the signals

being misunderstood will be entirely eliminated.

What I claim and desire to secure by Letters-Patent is:

In a device of the character described, a 25 casing having a side opening, a tubular housing leading from a driver's position to the casing and having a slot with selector notches opening to the slot, a signal element pivoted in the casing and tiltable 30 through said side opening, a link pivoted to the signal element, a bar in the housing pivoted to said link, a flexible member connected with the bar, an arm connected with the flexible member, and a handle stem on 35 the arm selectively engageable in said notches to retain the signal element in corresponding signaling position.

In testimony whereof I affix my signature.

JOHN C. McVEY.
